United States Patent Office

Des. 189,790
Patented Feb. 21, 1961

189,790

TOY HOBBYHORSE VEHICLE

John R. Parks, Palatine, Ill., assignor to Marvin I. Glass,
Chicago, Ill.

Filed Sept. 9, 1960, Ser. No. 62,078

Term of patent 14 years

(Cl. D34—15)

I claim:

The ornamental design for a toy hobbyhorse vehicle, substantially as shown.
